UNITED STATES PATENT OFFICE.

WALKER JULIAN BOND, OF ATOKA, INDIAN TERRITORY.

LUMBER-WAGON.

SPECIFICATION forming part of Letters Patent No. 608,644, dated August 9, 1898.

Application filed February 21, 1898. Serial No. 671,107. (No model.)

To all whom it may concern:

Be it known that I, WALKER JULIAN BOND, a citizen of the United States, residing at Atoka, in the Choctaw Nation, Indian Territory, have invented a new and useful Lumber-Wagon, of which the following is a specification.

My invention relates to lumber-wagons, and has for its object to provide such wagons with improved means whereby the whole load of lumber may be dumped at once.

With this object in view my invention consists in a lumber-wagon comprising front and rear wheels, axles, and bolsters, and a coupling-pole pivotally secured to the front bolster and slidably secured to the rear bolster, whereby when the rear wheels are chocked the load may be tilted on the rear bolster as a pivot by backing the team.

My invention further consists in a lumber-wagon provided with front and rear wheels, axles, and bolsters, a coupling-pole pivotally secured to the front bolster and slidably secured to the rear bolster, a frame secured to the front bolster and extending across the wagon to prevent the lumber from being projected too far over the front bolster, and a friction-roller journaled on the rear bolster, whereby by chocking the rear wheels and backing the team the load of lumber may be tilted on the rear bolster.

My invention further consists in the improved construction, arrangement, and combination of parts hereinafter fully described and afterward specifically pointed out in the appended claims.

In order to enable others skilled in the art to which my invention most nearly appertains to make and use the same, I will now proceed to describe its construction and operation, reference being had to the accompanying drawings, forming part of this specification, in which—

Figure 1 is a top plan view of a lumber-wagon constructed in accordance with my invention. Fig. 2 is a longitudinal section through the same on the line 2 2 of Fig. 1 with a load of lumber thereon, the front part of the lumber being broken away. Fig. 3 is a longitudinal section on the line 3 3 of Fig. 1 with the load of lumber thereon, the lumber being

also shown in dotted lines in its tilted position. Fig. 4 is a detail perspective view of the front cage or frame and bolster. Fig. 5 is a detail perspective view of the rear bolster and roller, looking at the front thereof. Fig. 6 is a detail perspective view of the rear bolster and roller, looking at the rear thereof, the central portion of the hinged bar being broken away.

Like numerals of reference mark the same parts wherever they occur in the various figures of the drawings.

Referring to the drawings by numerals, 10 and 11 indicate the front and rear wheels, mounted, as shown, upon axles 12 and 13, the usual bolsters 14 and 15 being mounted upon the front and rear axles, respectively.

16 indicates the coupling-pole, connected to the front axle by the king-bolt 17 and passed through a mortise 18 in the rear bolster 15.

19 and 20 indicate the front and rear hounds, the rear hounds being provided at their front end with a sleeve 21, through which the coupling-pole 16 freely passes, said coupling-pole being prevented from being drawn forward through the mortise 18 in the rear bolster by means of a pin 22. Upon the front bolster is mounted a cage or frame 23, and from the rear bolster bearings 24 project forward in position to receive the pivots of a roller 25, extending from end to end of the bolster across the wagon and projecting slightly above the upper surface of the bolster. A cross-bar 26 is connected to the rear bolster by means of hinges 27, and in its normal position, as shown in Figs. 2 and 6, it rests upon the upper surface of the rear bolster, the upper surface of said hinged bar being slightly higher than the upper surface of the roller 25.

A slide-bolt 28, secured to the rear side of the hinged bar 26, serves when in its normal position, as shown in Fig. 6, to hold the hinged bar in its normal position upon the upper surface of the bolster; but when the bolt 28 is withdrawn upward the hinged bar 26 will be free to turn on its hinges.

The construction of my invention will be readily understood from the foregoing description, and its operation may be described as follows: In loading the lumber upon the wagon the forward ends are laid upon the front bolster, projecting into the cage 23, while

near the rear the lumber rests upon the upper surface of the hinged bar 26, which at this time is in its normal position, as shown in Figs. 2 and 6, with the bolt 28 pressed downward. 5 When it is desired to unload the lumber from the wagon, the rear wheels are chocked by means of a stone or other obstruction, as at 29, or by a chain around the spokes of the rear wheel, and braces 30 are provided to connect the front bolster 19 with the coupling-pole 16, so as to prevent the front axle turning on the pole. The team is now backed, which will cause the front wheels to be moved backward, while the rear wheels are stationary, 10 the engagement of the front end of the load of lumber with the frame 23 causing the lumber to be moved backward also. In the meantime the bolt 28 has been knocked upward, so that the first motion backward of the lumber while resting upon the top of the hinged bar 26 will cause said hinged bar to be tilted upon its hinges and the lumber to rest upon the upper surface of the roller 25, by which means it can be more readily forced backward with the front axle. As soon as the lumber has been pushed backward sufficiently far to bring the center of gravity of the load in the rear of the roller 25 the rear end of the load will drop to the ground, as 15 shown in dotted lines in Fig. 3, when the team can be pulled forward, drawing the wagon out to its full length and then drawing the rear wheels, axles, bolsters, and roller out from under the load, permitting the forward end to drop upon the ground, so that the whole load is dumped in one operation, thus dispensing with the necessity of unloading it piece by piece and greatly economizing the time of the driver. The usual standards 31 and 32 20 are provided upon the front and rear bolsters, respectively, to prevent the displacement of the load sidewise.

While I have illustrated and described the best means now known to me for carrying out my invention, I do not wish to be understood as restricting myself to the exact details of construction shown, but hold that such slight changes as might suggest themselves to the ordinary mechanic would fall within the limit 45 and scope of my invention.

Having thus fully described my invention,

what I claim as new, and desire to secure by Letters Patent of the United States, is—

1. In a lumber-wagon, comprising the usual front and rear wheels, axles and bolsters, the combination therewith of a coupling-pole, pivotally connected to the front bolster and slidably connected to the rear bolster, a cage, mounted upon the front bolster to receive the forward end of the load of lumber, and a roller, mounted parallel with the rear bolster upon bearings projecting therefrom and having its upper surface slightly higher than the upper surface of the bolster, substantially as described. 60 65

2. The combination in a lumber-wagon, of the usual front and rear wheels, axles and bolsters, a coupling-pole, pivotally connected to the front bolster, rear hounds, projecting from the rear axle forward and provided at 70 their forward meeting ends with a sleeve, through which the coupling-pole passes, and a pin in the coupling-pole, in the rear of the rear bolster, substantially as described.

3. The combination in a lumber-wagon, of 75 the rear bolster, the roller mounted in bearings thereon, parallel with the bolster and having its upper surface slightly higher than the upper surface of the bolster, and a cross-bar, hinged to the bolster, parallel with the 80 roller and having its upper surface slightly higher than the upper surface of the roller, substantially as described.

4. The combination in a lumber-wagon, of 85 the rear bolster, the roller mounted in bearings thereon, parallel with the bolster and having its upper surface slightly higher than the upper surface of the bolster, a cross-bar, hinged to the bolster, parallel with the roller and having its upper surface slightly higher 90 than the upper surface of the roller, the normal position of the cross-bar being upon the top of the bolster, and a vertically-sliding bolt, mounted on the hinged bar and engaging the rear surface of the bolster to hold the 95 hinged bar in its normal position, substantially as described.

WALKER JULIAN BOND.
